UNITED STATES PATENT OFFICE.

CHARLES C. HENDERSON AND JACOB R. HENDERSON, OF ARKADELPHIA,
ARKANSAS.

CLOTH-MEASURING MACHINE.

SPECIFICATION forming part of Letters Patent No. 242,641, dated June 7, 1881.

Application filed November 26, 1880. (Model.)

To all whom it may concern:

Be it known that we, CHARLES C. HENDERSON and JACOB R. HENDERSON, of Arkadelphia, Clark county, and State of Arkansas, have invented certain new and useful Improvements in Machines for Measuring Bagging and other Materials, of which the following is a specification.

Our improvements relate to machines for winding off and measuring bagging and heavy bolt goods, and have for their object to save the time and labor required in doing such work by hand. Further, the object is specially to relieve the counting-shaft of weight from the passing web, and to construct counting mechanism adapted for measuring large quantities at once.

In the accompanying drawings, Figure 1 is a front elevation of the machine partially in section. Fig. 2 is a vertical section of the same, and Fig. 3 is a face view of the registering-dial.

Similar letters of reference indicate corresponding parts.

25 A are standards fixed to a base, B, or they may be otherwise supported. At the upper ends of standards A are fixed cross-bars a a, in which tension-rollers b are fitted, there being two rollers, b, at each end of bars a, so that 30 there is a pair of such rollers at each side of the machine. In the standards is journaled a shaft, c, on which is fixed a circular disk, d, having pins on its edge. The shaft c is placed so that the upper edge of disk d is about on 35 a straight line from the front rollers, b, to the rollers at the back, the pins being thereby in position for being caught by the web passing across without there being any weight on shaft c from the material. One end of shaft c is 40 fitted with a worm, e, projecting outside the standard into a box, f, in which box, on an arbor, g', is fitted a pinion, g, that engages with the worm. On the arbor g', at the outside of the box, is a loose dial, h, and fixed on 45 the arbor is a hand or pointer, i. The dial h is marked in yards, and has numerous holes near its edge, which allow a pin to be inserted into the side of box f, to hold the dial after it is turned to bring the zero-point to the hand. 50 This mechanism will register the turns of shaft

e, and is specially adapted for indicating large quantities by a single turn of the pointer. In measuring smaller quantities—as, for instance, in retailing goods—a quicker-acting counter can be used.

On the lower part of standards A are fixed cross-bars k, which carry at the front of the machine the windlass-shaft B, by which the material is to be wound. The shaft B is made in three portions, the two end portions, l l', 60 supported in cross-bars k, and middle bar or board, m, that is connected removably to the ends of the portions l l'. The end portions are each fitted with two plates, n, having toothed edges, between which the end of board or bar 65 m is clamped by a screw, n, tapped into the plates. This construction permits ready removal of the bar or board m with the roll of material.

The rear ends of cross-bars k sustain a rigid 70 bar, o, over which the material passes to the tension-rollers b. This bar may be dispensed with when the machine is used for heavy material, and, if desired, the ends of arms k may have pins p, for stretching the bagging while a new 75 roll is being attached to the end of an exhausted roll.

In operation the roll of material is placed upon the floor, the end drawn from the inside over one of the lower rollers, under and half 80 around the adjacent upper roller, across the face of the disk, over and half around the other upper roller, and over and within the other lower roller, down to the windlass-shaft C, so that the upper rollers serve to hold said mate- 85 rial within reach of the pins of the disk without allowing it to bear upon the disk itself, while the lower rollers serve to keep the material at a greater tension than would otherwise be the case. As the material is wound 90 on the board m the shaft c is turned and the quantity drawn over indicated on the dial. The dial is in convenient position for observation, and the pointer moving slowly a large number of yards will be registered in a single 95 revolution.

The separate portions l l' of shaft being capable of end movement in the supports k, a bar or board, m, suited to the width of mate- rial can be used.

Having thus described our invention, we claim as new and desire to secure by Letters Patent—

The combination, with the disk *d*, carrying 5 peripheral pins and arranged upon a rotary shaft, *c*, of the two pairs of rolls *b b*, arranged on opposite sides of the upper part of disks, serving both to hold the cloth above the disk,

but within reach of the pins, and to regulate the tension of the cloth, as shown and described.

CHARLES C. HENDERSON.
JACOB R. HENDERSON.
